(57) **CLAIM**

The ornamental design for a relay replacement assembly, as shown and described.

DESCRIPTION

FIG. 1 is a perspective view of a relay replacement assembly;

FIG. 2 is a front view thereof;

FIG. 3 is a top view thereof;

FIG. 4 is a bottom view thereof;

FIG. 5 is a right view thereof;

FIG. 6 is a left view thereof;

FIG. 7 is a back view thereof;

FIG. 8 is another perspective view thereof;

FIG. 9 is an exploded perspective view thereof; and,

FIG. 10 is an exploded perspective view thereof including optional components.

The broken lines in the figure drawings are included for the purpose of illustrating unclaimed environment and forms no part of the claimed design.
